United States Patent Office.

WILLIAM LEHMAN, OF NEWVILLE, PENNSYLVANIA.

Letters Patent No. 78,295, dated May 26, 1868.

IMPROVED COMPOSITION TO BE APPLIED TO LEATHER.

The Schedule referred to in these Letters Patent and making part of the same.

TO ALL WHOM IT MAY CONCERN:

Be it known that I, WILLIAM LEHMAN, of Newville, county of Cumberland, and State of Pennsylvania, have invented a new Composition for making water-proof and preserving boots, shoes, harness, straps, bellows, and leather-manufactured articles in general; and I do hereby declare that the following is a full and exact description thereof.

The nature of my invention consists in mixing together, at certain temperatures, whale-oil, beef tallow, hog's lard, lamp-black, beeswax, and indigo, in such proportions as to bring about the above-specified results.

To enable others to use my composition, I will state that the leather should be well cleaned, the composition applied, and rubbed in, by the heat of a stove or the sun, until the pores of the leather are filled. After a few minutes, the leather may be rubbed with a cloth, so as to remove any loose matter that may be on the surface of it. This process will give the leather a new and healthy appearance, make it water-proof, and add one hundred per cent. to its durability.

What I claim as my invention, and desire to secure by Letters Patent, is—

The application of the composition herein described to boots, shoes, harness, straps, bellows, and leather-manufactured articles generally, by which the same will become water-proof, and wear one hundred per cent. longer.

WILLIAM LEHMAN.
